[57] CLAIM

The ornamental design for a combined traction and hydrotherapy tub, as shown and described.

DESCRIPTION

FIG. 1 is a top perspective view of a combined traction and hydrotherapy tub, showing my new design; FIG. 2 is a top plan view thereof; FIG. 3 is a side elevational view thereof; FIG. 4 is a cross-sectional view thereof taken along line 4—4 of FIG. 3; FIG. 5 is a rear elevational view thereof; and FIG. 6 is a side elevational view thereof, opposite that shown in FIG. 3.

FIG. 2

FIG. 1

FIG. 6

FIG. 5
